MOVING TRAFFIC SIGNAL DEVICE

John E. Swanger, Canton, N. C., assignor of one-half to Alfred T. Swanger, Canton, N. C.

Application January 11, 1951, Serial No. 205,456

9 Claims. (Cl. 340—74)

1

This invention comprises novel and useful improvements in traffic control devices, and more particularly pertains to control devices for regulating the speed of vehicles in traffic control zones.

An important object of this invention is to provide a traffic control device for regulating the speed of traffic in both directions in a traffic control zone.

An important feature of this invention resides in the provision of a traffic control device which is movable parallel to the vehicle roadway at a predetermined rate of speed and which device carries a traffic control light which is directed in opposition to the direction of movement of the traffic control device to control the speed of the traffic which is moving in the same direction as the control device.

Another feature of this invention resides in the provision of a traffic control device, in accordance with the foregoing feature together with a means for selectively reversing the direction of movement of the traffic control device and for simultaneously changing the light so that it is directed in opposition to the direction of movement of the device.

A further feature of this invention resides in the provision of a track for supporting the traffic control device, constructed in accordance with the foregoing features, with a means carried by the track for actuating the reversing mechanism for the traffic control device and light.

Still another feature of this invention resides in the provision of a pair of traffic control devices which are movable over the traffic control zone in opposite directions to each other to regulate the traffic going in opposite directions, together with a mechanism for selectively reversing both devices, and the lights carried thereby.

These, together with various ancillary objects and features are attained by this device, a preferred embodiment of which has been illustrated by way of example only in the accompanying drawings wherein:

Figure 1 is a fragmentary perspective elevational view of a traffic control zone with the control device shown mounted for movement parallel to the zone;

Figure 2 is a side elevational view of the traffic control device;

Figure 3 is an end elevational view of the traffic control device;

Figure 4 is a top plan view of the traffic control device;

Figure 5 is a transverse sectional view of the

2

traffic control device, taken on the plane 5—5 of Figure 2; and,

Figure 6 is a diagrammatic view of the wiring circuit of the traffic control device.

Reference is now made more specifically to the accompanying drawings wherein the traffic control device is indicated generally by the numeral 10.

The traffic control device is adapted to be supported by a pair of parallel track wires 12 and 14 which are supported by transverse cross wires 16 carried by poles 18. As will be noted, the track wires 12 and 14 extend parallel to and vertically spaced from the center line 20 of the vehicle roadway 22, and that the cross wires 16 are reinforced by suitable guy wires 24. As it is intended that the track wires 12 and 14 serve as conductors by means of which power is supplied to the traffic control device, it will be appreciated that the same must be suitably insulated from each other and from the ground.

The traffic control device 10 includes a housing 26 having journals 28 thereon for rotatably receiving the shafts 30. Grooved wheels 32 are carried by the ends of the shafts 30 and are disposed on the track wires 12 and 14. It is contemplated that the wheels serve as current collectors, although other suitable means such as brushes may be utilized. In utilizing the wheels 32 as collectors, it is apparent that the wheels 30 of each pair must be insulated from each other, and that they may be electrically connected to the traffic control device in any conventional manner. As the specific manner of electrically connecting the traffic control device to the support wheels 32 forms no part of this invention, and as the various alternative means for electrically connecting the same are well known to those skilled in the art, further description is believed unnecessary.

In order to drive the traffic control device, the device is provided with a motor 34 which is disposed within the housing 26, the pulley 36 carried by the motor shaft being operatively connected as by the belt 38 to the pulley 40 on one of the supporting shafts 30.

A first and a second traffic control light 42 and 44, respectively are disposed in a casing 46, carried by the housing 26, each of which lights are directed in opposition to each other parallel to the path of movement of the traffic control device.

The intended operation of the device thus far described is as follows:

The traffic control device 10 is moved at a predetermined rate of speed by the motor 34, in one

direction, and at the same time the traffic light which is directed in opposition to the direction of movement is actuated, and the other traffic light deactuated. The rate of travel of the traffic control device is regulated so that it moves at the maximum rate speed prescribed for the traffic control zone, the actuated light warning motorists on the vehicle roadway therebelow, and which are moving in the same direction as the traffic control device that they should not pass under the light that is actuated, thereby regulating the speed of the traffic. In order to return the traffic control device to its starting position, it will be appreciated that there may be provided a continuous oval track. However, it has been found desirable to provide a track, as is shown in the accompanying drawings and selectively reverse the direction of movement of the traffic control device and to reverse the traffic control lights. It is also contemplated that a single traffic light may be utilized, the same being movably mounted on the device, so as to be reversible relative thereto, when the direction of movement of the light is reversed.

It is preferred that two or more traffic control devices be utilized for each zone, although it will be appreciated that a single control device may also be utilized without departing from the spirit of this invention. When two control devices are utilized, they are moved in opposite directions to each other and reverse at the midpoint and at the end of the zone, whereby one traffic control device regulates traffic moving in one direction to the midpoint of the zone, at which time it reverses and controls the traffic moving in the opposite direction, the other traffic control device, after reversing and moving away from the midpoint of the control zone regulating the traffic formerly regulated by the first traffic control device. Obviously, when additional traffic control devices are utilized, because of the length of the traffic control zone, then they are synchronized with the other devices, to move in relatively opposite directions to the adjacent traffic control devices.

In order to reverse the direction of movement of the traffic control device, and to also reverse the lights carried thereby, there may be provided a common time actuated reversing switch mounted adjacent the control zone, which selectively reverses the motor 34, and through a suitable mechanism also reverses the lights 42 and 44. The reversing mechanism, shown in the drawings is actuated in response to a predetermined travel of the traffic control device, and includes an L-shaped crank arm 48 having a bifurcated end 50 which has a guide wheel 52 rotatably mounted therebetween for engagement with one of the guide tracks. The other leg of the crank arm is rotatably disposed through bores in the housing 26, and a compression spring 54 is attached to the housing and crank arm to urge the latter out of a dead center position in which the bifurcated end 50 thereof is disposed vertically.

In order to reverse the motor 34, there is provided a reversing switch 56 which is operatively connected by lever 58 to the crank arm 48. A pair of light switches 60 and 62 are carried by the housing 26, each of which light switches is adapted to be engaged by the crank arm 48, when the latter is in either off-center position, to thereby actuate one of the lights 42 or 44.

The motor 34 is connected by conductors 64 to the collector and support wheels 34 and to

the reversing switch 56 by conductors 66. The light switch 60 is connected by conductor 68 to one collector wheel, and is otherwise connected as by conductor 70 to the light 44, the latter 5 being otherwise electrically connected by conductors 72 and 64 to the other collector wheel. The light switch 62 is also connected to one collector wheel, as by conductors 74 and 68, the switch being otherwise connected to the light 10 42 by conductor 76, and which light is otherwise connected by conductors 78 and 64 to the other of the collector wheels.

Whenever the traffic control device is moving to the left, as is viewed in Figure 6, then the 15 switch 60 will be closed by the bell crank 48, and the light 44, directed in opposition to the direction of movement of the traffic control device will be actuated. The wheel 52 on the end of the crank arm engages an abutment 80 disposed on the track wires adjacent the ends and at intermediate points in the traffic control zone. This causes the crank arm to pivot about its 20 axis, into the opposite off-center position, in which it is retained by the spring 54. The crank arm, through the link 58 shifts the reversing switch 56 into its reverse position to change the direction of movement of the traffic control device. Simultaneously, the switch 60 is deactivated and returned to its inoperative position by 25 a spring (not shown) and the switch 62 is actuated, thereby energizing the light 42 while de-energizing the light 44.

It will thus be seen that the traffic control device 10 and the lights 42 and 44 carried thereby 30 are reversed each time the guide wheel 52 engages one of the abutments 80, whereby the traffic control device is cyclically moved in opposite directions, and that light which is directed in opposition to the direction of movement of the 35 control device is energized to regulate the rate of travel of the vehicles moving in the same direction as the traffic control device. Further, it will be noted that when two or more traffic control devices are utilized that they will jointly 40 serve to control traffic moving in both directions, each device controlling the traffic moving in one direction for a portion of the zone and then reversing and controlling the traffic moving in the opposite direction. Since the light which is 45 directed in the direction of movement of the traffic control device is deactuated, it will be appreciated that the device will not control the traffic moving in opposition to the direction of movement of the control device.

Having described the invention, what is claimed as new is:

1. A traffic controlling device comprising a traffic control light, track means extending parallel to a vehicle roadway for supporting said light 60 thereabove, housing means movably mounting said light on said track means carried by said housing means, means for moving said light on said track means at a predetermined rate of speed to regulate the rate of movement of the traffic 65 on the roadway therebelow.

2. A traffic control device comprising a traffic control light, track means extending parallel to and above a vehicle roadway for supporting said light, housing means movably mounting said light on said track means, means carried by said housing means for moving said light on said track means at a predetermined rate of speed to regulate the movement of traffic on the roadway therebelow.

3. A traffic control device comprising a traffic

control light, track means extending parallel to a vehicle roadway for supporting said light thereabove, housing means movably mounting said light on said track means, impelling means carried by said light for moving said light on said track means at a predetermined rate of speed to regulate the movement of traffic on the roadway therebelow, means for selectively reversing the direction of movement of said light.

4. A traffic signal device comprising a housing, track means extending parallel to a vehicle roadway for supporting said housing, means movably mounting said housing on said track means, first and second traffic control lights carried by said housing in opposing relation to each other, means for moving said housing on said track means, means for selectively reversing the direction of movement of said housing, and means for selectively energizing that one of the lights carried by said housing which is directed in opposition to the direction of movement of said housing.

5. A traffic signal device comprising a housing, means extending parallel to a vehicle roadway for supporting said housing means movably mounting said housing on said supporting means for movement parallel to said highway, a first and a second traffic control light carried by said housing in opposing relation and directed parallel to the path of movement of said housing, means carried by said housing for driving said housing on said support means, means for reversing the direction of movement of said housing, means for actuating the light directed opposite to the direction of movement of said housing and for deactuating the other of said lights.

6. A traffic signal device comprising a housing, means extending parallel to a vehicle roadway for supporting said housing, means movably mounting said housing on said supporting means for movement parallel to said highway, a first and a second traffic control light carried by said housing in opposing relation and directed parallel to the path of movement of said housing, means carried by said housing for driving said housing on said support means, means for reversing the direction of movement of said housing, means for actuating the light directed opposite to the direction of movement of said housing and for deactuating the other of said lights, means carried by said support means for actuating said reverse means when said light reaches a predetermined position.

7. A traffic signal device comprising a housing, means extending parallel to a vehicle roadway for supporting said housing, means movably

mounting said housing on said supporting means for movement parallel to said highway, a first and a second traffic control light carried by said housing in opposing relation and directed parallel to the path of movement of said housing, means carried by said housing for driving said housing on said support means, means for reversing the direction of movement of said housing, means for actuating the light directed opposite to the direction of movement of said housing and for deactuating the other of said lights, means carried by said support means for actuating said reverse means and for controlling said light actuating means when said housing reaches a predetermined position on said support means.

8. A traffic control system comprising a first and a second traffic control unit, a pair of lights in each unit disposed in opposing relation to each other, means for supporting said control units for movement parallel to a vehicle highway, means for driving said control units in opposite directions to each other on said support means at a predetermined rate of speed, means for reversing the direction of movement of each of said control units when said units reach the midpoint and the ends of said support means, and means for actuating that light of each unit which is disposed in opposition to the direction of travel of the units.

9. A traffic control system comprising a pair of parallel track members, a housing, shafts mounted on said housing, grooved wheels carried by said shafts and disposed on said track elements, a motor disposed within said housing, said motor being operatively connected to one of said shafts, a first and second traffic control light carried by the housing, said lights being directed in opposition to each other and parallel to the path of movement of said housing, a control lever mounted on said housing, means for reversing the position of said lever, a motor reversing switch actuated by said lever, switch means for each of said lights, said switch means being selectively actuated by said lever for energizing that light directed opposite to the direction of movement of said housing.
